EX

OR D 13,280

DESIGN FOR A STOVE.

Design No. 13,280, dated August 29, 1882.

UNITED STATES PATENT OFFICE.

JAFEW S. VAN BUREN, OF ALBANY, NEW YORK.

DESIGN FOR A STOVE.

SPECIFICATION forming part of Design No. 13,280, dated August 29, 1882.

Application filed July 20, 1882. Term of patent 7 years.

To all whom it may concern:

Be it known that I, JAFEW S. VAN BUREN, of Albany, in the county of Albany and State of New York, have invented certain new and useful Improvements in Designs for Stoves; and I do hereby declare the following to be a full, clear, and exact description of the invention, such as will enable others skilled in the art to which it pertains to make and use it, reference being had to the accompanying drawings, which form part of this specification.

My invention relates to an improvement in designs for stoves; and it consists in the designs and configurations which are formed upon the different doors of the stove, as will be more fully described hereinafter.

The accompanying wood-cut represents my invention.

Upon the door A, which closes the end of the fire-chamber, there is made across the center of the door an oblong figure, the ends of which are slightly pointed, and in the center of which is the representation of a branch with leaves. Upon opposite sides of this oblong figure, inclosing the branch, are the two semicircles, which are connected together at their ends, as shown. From the opposite corners of the two oblong figures run straight lines, which are bent at right angles, and which have their ends then bent and curved, as shown.

Upon the oven-door B there is formed a curved line, which forms the greater part of a circle, and which has its ends curved outward, as shown, so as to cross each other. In this pointed portion formed by the crossing ends is a representation of a small branch or other similar design. Inside of the curved portion of the circle is a small curve, and these two curved lines are jointed together by radial lines, as shown. Inside of the curved lines are formed the four figures D, in between which are placed the radial lines, terminating in a small ball or bulb, and in the center of these figures is a small circle. Upon opposite sides of the two curved lines are the segments of a circle, E, which have curved lines running back and forth across them, as shown. Radiating from the circles or curved lines are

three straight lines, upon the outer sides of the outer ones of which are formed the figures or designs shown. Extending diagonally away from the knob of the door is a small ornamental design, G, as shown. Extending around the edge of the flat portion of the door is an encircling line, H, which is continuous all around, with the exception of upon the bottom. Upon the bottom this line is broken, as shown, for the purpose of forming a triangular figure near each corner.

Upon the door L there is formed a star-shaped figure in the center, around which are drawn two circles. Around these circles is a circular line, which is united to the circles at different points by radial cross-lines. Radiating from opposite sides of the two circles toward opposite corners of the door are two straight lines, through which other curved lines radiate. Upon opposite sides of the circles are the two segments, O, which have a number of curved lines running back and forth across them. From the top and bottom of the two circles radiate straight lines, which then bend at right angles, so as to follow the shape of the door.

Upon the lower door, M, is formed a small circle, and around this small circle is formed a larger one, and in between the two circles are formed a number of angular figures, as shown. Upon the top and bottom of the outer circle are formed the two segments, which are crossed at regular intervals by a series of radiating lines. Outside of these segments are formed the two curved lines which meet the radial lines which extend out toward the corners of the stoves. Radiating from the larger circle toward the back of the stove is a small ornamental design similar to a branch having leaves.

Each one of the feet of the stove has a recessed portion near its top, in which are formed a number of drops, and the lower edge of this recessed portion is made scalloped, as shown. Upon the extreme front edges of the feet is formed an ornamental design, as shown, and upon the sides are formed angular figures.

I do not limit myself to the manner in which these designs are formed, for they may either

(over)

be indented in the doors or raised thereon in any suitable manner.

Having thus described my invention, I claim—

- 5 1. The design upon the door A, as shown.
2. The design upon the door B, as shown.
3. The design upon the door L, as described.
4. The design upon the door M, as specified.

In testimony whereof I affix my signature in presence of two witnesses.

JAFEW S. VAN BUREN.

Witnesses:

J. T. REIFSNIDER,
JAMES VANDERPOEL.
